UNITED STATES PATENT OFFICE.

CHARLES SCHWITTER, OF BROOKLYN, NEW YORK.

ART OF MAKING WATCH-CASES.

SPECIFICATION forming part of Letters Patent No. 257,083, dated April 25, 1882.

Application filed December 15, 1881. (No model.)

To all whom it may concern:

Be it known that I, CHARLES SCHWITTER, a citizen of Switzerland, residing at Brooklyn, in the county of Kings and State of New York, 5 have invented new and useful Improvements in Watch-Cases, of which the following is a specification.

This invention relates to the manufacture of covers for watch-cases, and has for its object to provide an improved method of making such covers, whereby time and labor are saved in their production.

To this end my invention consists in a method of making covers for watch-cases, which 15 consists in cutting or stamping out the rim, with its ornaments, from a blank of metal, then stamping up the head, and finally uniting the rim to the edges of the head by means of solder.

This invention is illustrated in the accompanying drawings, in which—

Figure 1 represents an inside view of the cover for a watch-case constructed according to my invention. Fig. 2 is a transverse section of the same in the plane xx , Fig. 1. Fig. 3 is a 25 similar section of the rim and the head detached.

Similar letters indicate corresponding parts.

In watch-cases with ornamental rims the rims are usually constructed separate from the 30 ornaments, and then the ornaments are secured to the edges of the rims by solder. For the purpose of forming the rim a straight bar of metal is rolled or drawn to the required shape, and after having been cut to the required shape 35 this bar is formed into a ring, its ends being secured together by means of solder.

For the purpose of manufacturing my watch-case I roll out a piece of silver, gold, or other metal suitable for the purpose of the thickness desired, and from that sheet I cut out by means 40 of suitable dies the rim A, together with the desired ornaments aa , in one piece, (see Fig. 3,) and then I cut out a blank of suitable size, and from this blank I stamp up the head B in the form shown in Fig. 3, and finally I secure 45 the head to the rim by means of solder.

It will be readily seen from this description that in manufacturing watch-cases with ornamental rims according to my invention much time and labor are saved, and, furthermore, a 50 great variety of ornamental rims can be produced by providing different dies.

What I claim as new, and desire to secure by Letters Patent, is—

The method herein described of making covers for watch-cases, which consists in cutting or stamping out the ornamental rim A in a single homogeneous piece of metal, then stamping or striking up from a blank the head B, and finally uniting the rim to the edges of the 60 head by means of solder, substantially in the manner and for the purpose described.

In testimony whereof I have hereunto set my hand and seal in the presence of two subscribing witnesses.

CHARLES SCHWITTER. [L. S.]
